UNITED STATES PATENT OFFICE.

MAX MILLER, OF NEW YORK, N. Y.

BUILDING UNIT.

Application filed December 22, 1926. Serial No. 156,286.

This invention relates to reinforced concrete building units, adapted for use individually, as beams, girders and the like; and also adapted for use collectively in building up a desired structure, such for example as a floor.

A general object of the invention is to provide a unit of the character mentioned in which the component elements thereof may be cheaply manufactured, easily assembled and so reinforced as to lend rigidity and strength to the unit in its entirety.

Other objects and advantages of the invention will become apparent from the following description when taken in connection with the accompanying drawings.

Figure 1 is a fragmental perspective view of a floor structure made up of a plurality of units embodying the invention. Figure 2 is an end view of a plurality of sections, showing the concrete, which is employed to unite the adjacent sections of the units, as broken away. Figure 3 is a view partly in elevation and partly in section, showing the keying concrete as filling the space between adjacent ends of the sections. Figure 4 is a plan view of the sections arranged in an end to end relation prior to their being united through the instrumentality of interposed concrete. Figure 5 is a detail view showing a fastening device for the meeting ends of a reinforcing bar. Figure 6 is a view similar to Figure 4 and showing reinforcing bars of the type employed in connection with the end sections of Figure 4 as adapted for use in connection with all of the sections. Figure 7 is a diagrammatic view showing a reinforcing bar embracing end sections at opposite sides of an I-beam.

In building up a floor, for example, a plurality of units may be employed, which units are adapted to be arranged side by side, and include a plurality of sections 5, arranged end to end in a spaced relation so as to permit the use of a keying cement or concrete 6 as a medium for uniting the sections of each unit and for locking the units together transversely.

The sections 5 are adapted to be pre-formed or cast from concrete in suitable molds so designed as to provide each section along its upper longitudinal corners with parallel grooves 7. The grooves 7 of one section form with

the adjacent grooves 7 of the adjacent sections, a plurality of channels 8 when the sections are arranged in a side to side relation, the channels 8 thus formed being adapted for the reception of suitable bars or other reinforcing material, as will hereinafter appear.

In molding the sections 5, certain of these sections may be provided with U-shaped reinforcing bars 10, the major portions of which are embedded in the concrete relatively near the lower face thereof. The curved portion of each of these reinforcing bars 10 projects an appreciable distance from one end of the section, and the ends of such bar are bent back upon themselves, as shown in Figure 4, thus providing loops, or yoke-like portions 11, which serve to effectively anchor the bar 10 against longitudinal movement with respect to the section carrying the same. In molding certain other sections, a reinforcing bar 12, such as that shown in connection with the intermediate section of Figure 4, may be employed. This reinforcing bar 12 is molded into the section carrying the same, but instead of having its ends turned back in order to provide loops or yoke-like portions, such as are indicated by the numeral 11, such ends may project from the end of the section, thereby forming fingers 13 which are adapted to be suitably connected together, thus forming yoke-like portions as at the opposite end of the section. While the ends of these fingers 13 may be connected in various ways, a fastening device such as is shown in detail in Figure 5 has been found satisfactory, which fastening device comprises a strap 14 having its opposite ends bolted to the ends of the fingers 13.

Instead of employing the type of reinforcing bar 12 shown in Figure 4, it has been found that for such reinforcing bar, a reinforcing bar of the type indicated by the numeral 10 as shown in connection with the end sections of Figure 4, may be satisfactorily substituted. In Figure 6, such a substitution is shown, with the result that use is made of a plurality of uniformly constructed reinforcing bars 10', the reinforcing bar 10' of the middle section of Figure 6 differing from the reinforcing bars of the adjacent sections only in that its looped ends or yoke-like portions 11' project an appreciable distance from one end of the section.

In incorporating the units into a building employing I-beams 16, for example, as a part of the frame, suitable temporary supports 17 may be provided. These temporary supports 17 are adapted to support opposite ends of the intermediate sections and one end of each end section, the other ends of the end sections being supported upon suitable supports, such for example, as fire-proofing housing 18 carried by the I-beams 16, and enclosing the lower flanges thereof. The temporary supports 17 are also adapted to support a plurality of spacers or blocks 19, at intervals, upon which is placed a suitable reinforcing material, such as a strip of expanded metal 20, underlying the projecting ends of the reinforcing bars 10 and 12 and 10', shown respectively in Figures 4 and 6. A similar strip of expanded metal 20' may be placed upon the projected ends of the reinforcing bars 10 and 12 and 10', respectively. Since the corresponding sections of each unit are the same length, it follows that when a plurality of such units are placed in position side by side, as shown in Figure 1, transverse passages 21 are formed which extend parallel with respect to each other and with respect to the I-beams 16. These spaces 21 are adapted for the reception of a suitable keying material, such as concrete 22, which is poured into the passages and allowed to harden before the temporary supports 17 are removed. This concrete 22, when hardened, forms a transverse beam 21' which is reinforced by the expanded metal 20 and 20', which beam not only ties together the sections 5 of the units by reason of its interlocking engagement with the projecting portions of the reinforcing bars 10, 12 and 10', but also ties the units together transversely. Before pouring in the concrete 22, suitable reinforcing bars 23 are placed in position within the channels 8 which are formed by the adjacent grooves 7 in the end sections 5. These reinforcing bars 23 are preferably rectangular in shape and embrace the ends sections 5 at opposite sides of the I-beams 16, as shown diagrammatically in Figure 7. The reinforcing bars 23 are of such length that they project an appreciable distance into the space 21 so that when the concrete 22 is filled into such space the end sections 5 at opposite sides of the I-beams 16 are effectively tied together. If desired, reinforcing bars, similar to but of course shorter than those indicated by the numeral 23, may be placed within the channels 8 which are formed by the adjacent groove 7 in the intermediate sections 5.

In order to prevent excessive amounts of concrete 22 from entering the hollow sections 5, the ends of the passages 25, formed in such sections, may be closed with inserts 26, which are preferably constructed from suitable sheet metal and are formed with ears 27 which engage the ends of the sections 5 and

thereby insure the inserts from displacement. It will be noted that the end sections 5 are relieved or provided with grooves which are adapted to accommodate the upper flange of the I-beams 16. These grooves are sufficiently large to provide a relatively wide channel 30 which is adapted for the reception of concrete 22 of sufficient thickness to completely cover the sides of the reinforcing bars 23 at the ends of the adjacent sections 5, the remaining portions of the sides of the reinforcing bars 23 being covered by concrete 22 which is poured into the channels 8 carrying the bars 23.

After pouring the concrete 22 into the space 20, channels 8 and 30, respectively, the entire structure thus far assembled may be coated with a suitable cement 32 thereby giving the floor a smooth finish.

Having thus described certain embodiments of my invention what I claim is:

1. In combination, a pair of units, each comprising a plurality of sections arranged end to end in a spaced relation, common reinforcing means embracing the end sections of adjacent units, reinforcing bars embedded in the sections of each unit and projecting into the spaces afforded between said sections, reinforcing means overlying said projecting reinforcing bars, and a hardened plastic material carried within the spaces intermediate said sections and cooperating with said reinforcing material and said projecting reinforcing bars to lock said sections of each unit in an end to end relation.

2. In combination, a pair of units, each comprising a plurality of sections arranged end to end in a spaced relation and provided with grooves, common reinforcing means carried within the grooves of the end sections of adjacent units and embracing such sections, and a hardened plastic material carried within the spaces afforded between the sections of each unit.

3. In combination, a pair of units, each comprising a plurality of sections arranged end to end in a spaced relation and provided with grooves, common reinforcing means carried within the grooves of the end sections of adjacent units and embracing such sections, reinforcing bars embedded in the sections of each unit and projecting into the spaces afforded between said sections, and a hardened plastic material carried within the spaces intermediate said sections and cooperating with said projecting reinforcing bars to lock the sections of each unit in an end to end relation.

4. In combination, a pair of supports, spaced apart, a building unit supported at opposite ends by said supports and comprising a plurality of molded sections arranged end to end in a spaced relation, a hardened plastic material carried within the spaces intermediate said sections, and reinforcing

bars embedded within said sections and having yoke-like portions projecting into said hardened plastic material, said yoke-like portions embracing portions of said hardened plastic material whereby said hardened plastic material is interlocked with said yoke-like portions and said sections are anchored in an end to end relation, and reinforcing material overlying said yoke-like portions for a substantial distance and interlocked with said hardened plastic material.

5. In combination, a plurality of units arranged side by side, each unit comprising a plurality of sections arranged end to end in a spaced relation, the spaces afforded between adjacent sections of one unit being aligned with the spaces afforded between corresponding sections of the other units, a hardened plastic material molded into said spaces, reinforcing bars embedded in said sections and having yoke-like portions projecting into said hardened plastic material, said yoke-like portions embracing portions of said hardened plastic material whereby said hardened plastic material is interlocked with said yoke-like portions to connect together adjacent yoke-like portions of each unit and to connect said yoke-like portions of one unit to the yoke-like portions of adjacent units.

30. 6. In combination, a plurality of units arranged side by side, each unit comprising a plurality of sections arranged end to end in a spaced relation, the spaces afforded between adjacent sections of one unit being aligned with the spaces afforded between corresponding sections of the other units, a hardened plastic material molded into said spaces, reinforcing bars embedded in said sections and having yoke-like portions projecting into said hardened plastic material, said yoke-like portions embracing portions of said hardened plastic material whereby said hardened plastic material is interlocked with said yoke-like portions to connect together adjacent yoke-like portions of each unit and to connect said yoke-like portions of one unit to the yoke-like portions of adjacent units, reinforcing material within said spaces adjacent said yoke-like portions, said reinforcing material being arranged transversely of said units and embedded within said hardened plastic material.

7. In combination, a support, a pair of units arranged in an end to end relation and having their adjacent ends supported by said support, each of said units comprising a plurality of sections arranged end to end in a spaced relation, common reinforcing means looped about and embracing the upper margins of the end sections of adjacent units and a hardened plastic material carried within the spaces afforded between the sections of each unit.

8. In combination, a pair of units each comprising a plurality of sections arranged end

to end in a spaced relation, common reinforcing means looped about and embracing the upper margins of the end sections of adjacent units, a hardened plastic material carried within the spaces intermediate said sections, reinforcing bars embedded in said sections and having yoke-like portions projecting into said hardened plastic material, said yoke-like portions embracing portions of said hardened plastic material whereby said hardened plastic material is interlocked with said yoke-like portions and said sections are anchored in an end to end relation.

9. In combination, a pair of units each comprising a plurality of sections arranged end to end in a spaced relation, common reinforcing means looped about and embracing the upper margins of the end sections of adjacent units, a hardened plastic material carried within the spaces intermediate said sections, reinforcing bars embedded in said sections and having yoke-like portions projecting into said hardened plastic material, said yoke-like portions embracing portions of said hardened plastic material whereby said hardened plastic material is interlocked with said yoke-like portions and said sections are anchored in an end to end relation, and reinforcing material arranged above and below said yoke-like portions and interlocked with said hardened plastic material.

10. In combination, a support, a pair of units arranged in an end to end relation and having their adjacent ends supported by said support, each of said units comprising a plurality of sections arranged end to end in a spaced relation, reinforcing means overlying said support and connected to the end sections of adjacent units, reinforcing bars embedded in the sections of each unit and projecting into the spaces afforded between said sections, and a hardened plastic material carried within the spaces intermediate said sections and cooperating with said projecting reinforcing bars to lock said sections of each unit in an end to end relation.

11. In combination, a support, a pair of units arranged in an end to end relation and having their adjacent ends supported by said support, each of said units comprising a plurality of sections arranged end to end in a spaced relation, the end sections of each of said units being provided with grooves in their upper margins, reinforcing means overlying said support and projecting into said grooves, and a hardened plastic material carried within said grooves and within the spaces afforded between the sections of each unit.

12. In combination, a support, a pair of units arranged in an end to end relation and having their adjacent ends supported by said support, each of said units comprising a plurality of sections arranged end to end in a spaced relation, the end sections of each of said units being provided with grooves in

their upper margins, reinforcing means overlying said support and projecting into said grooves, reinforcing bars embedded in the section of each unit and projecting into the spaces afforded between said sections, and a hardened plastic material carried within said grooves and said spaces and cooperating with

said reinforcing means to retain such means within said grooves and cooperating with said projecting reinforcing bars to lock the sections of each unit in an end to end relation. 10

In testimony whereof, I have affixed my signature to this specification.

MAX MILLER.
